US00D987362S

(12) **United States Design Patent** (10) **Patent No.:** **US D987,362 S**
(45) **Date of Patent:** **** May 30, 2023**

(54) **HEATING BASE**

(71) Applicant: **Guangdong Shunde Mingyou Electric Co., Ltd.**, Foshan (CN)

(72) Inventor: **Houbing Yuan**, Foshan (CN)

(**) Term: **15 Years**

(21) Appl. No.: **29/779,012**

(22) Filed: **Apr. 15, 2021**

(51) LOC (14) Cl. **07-02**

(52) U.S. Cl.

USPC **D7/363**

(58) **Field of Classification Search**

(57) **CLAIM**

The ornamental design for a heating base, as shown and described.

DESCRIPTION

FIG. 1 is a perspective view of a heating base showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the heating base that form no part of the claimed design.

1 Claim, 8 Drawing Sheets
